(57) **CLAIM**

We claim the ornamental design for shotgun wad, as shown and described.

DESCRIPTION

FIG. 1 is a perspective view of a shotgun wad according to the invention. The view from the opposite side being identical thereto.

FIG. 2 is a perspective view of the shotgun wad of FIG. 1 with the fins in a deployed flared position after firing. The view from the opposite side being identical thereto.

FIG. 3 is an elevational view of the shotgun wad of FIG. 1. The view from the opposite side being identical thereto.

FIG. 4 is a perspective view of the shotgun wad of FIG. 1 with the fins in a deployed flared position after firing. The view from the opposite side being identical thereto.

FIG. 5 is a top end view of the shotgun wad of FIG. 1.

FIG. 6 is a bottom end view of the shotgun wad of FIG. 1. The portions shown in dashed lines are not part of the claimed invention.

FIGS. 1 through 24 of the appendix display alternate views and embodiments of the invention. Each shotgun wad shown is symmetrical with the view from the opposite side being identical thereto. The appendix figures may be deleted from the file upon allowance of the application to remain part of the prosecution file.
